GRINDING MACHINE

Paul S. Jackson, Rockford, Ill., assignor to Sundstrand Machine Tool Co., Rockford, Ill., a corporation of Illinois

Application May 3, 1933, Serial No. 669,151

15 Claims. (Cl. 51—124)

More particularly the invention relates to a machine for the sharpening or grinding of tools, it being an object of the invention to provide a new and improved machine of this character of simple construction and particularly adapted for the accurate and efficient sharpening of tools.

In sharpening tools, for example, those such as are used in connection with machine tools, it is generally desirable, if not necessary, to perform not only rough and finish grinding operations on the tool, but also to hone or lap the cutting edges of the tool. It is an object of the invention to provide a new and improved grinder embodying means for rough and finish grinding tools and also for honing the tools so that all of the finishing operations may be performed thereon.

In order to secure the best results from cutting tools the clearance angles, top rake and side rake must be carefully maintained. It is an object of the invention to provide a novel grinding machine having work supporting means enabling an operator readily and accurately to obtain and maintain the desired angles.

Another object is to provide a tool grinder of new and improved construction embodying work supports enabling the operator to hold the tools manually in contact with the grinding wheels and also adapted to clamp the tools mechanically in the proper position during the sharpening operation.

Another object is to provide a novel tool supporting mechanism for a grinding machine embodying means for oscillating the tool support and also means for feeding the tool support toward the wheel.

Another object is to provide a feeding mechanism for a work support embodying cushioning means operable if the tool being ground is fed too rapidly against the grinding wheel, to relieve any excessive tool pressure and to limit it to a predetermined pressure.

Another object is to provide a new and improved grinder embodying three grinding wheels together with simple and efficient means for driving the wheels from a single motor mounted in the base of the machine.

Another object of the invention is to provide improved means for supplying an abundant amount of coolant to the rough and finish grinding wheels.

Further objects and advantages will become readily apparent from the following detailed de-

scription taken in connection with the accompanying drawings, in which:

Fig. 1 is a front view of a preferred form of the invention.

Fig. 2 is a similar view partly in section along the line 2—2 of Fig. 4.

Fig. 3 is a fragmentary view looking at the right hand end of Fig. 2.

Fig. 4 is a vertical section approximately along the line 4—4 of Fig. 2.

Fig. 5 is a plan view, certain parts being shown in section.

Fig. 6 is an enlarged fragmentary view partly in section along the line 6—6 of Fig. 3.

Fig. 7 is a fragmentary section along the lines 7—7 of Figs. 5 and 6.

Fig. 8 is a fragmentary section along the line 8—8 of Fig. 6.

Fig. 9 is a plan view of one form of tool guide.

Fig. 10 is a section along the line 10—10 of Fig. 9.

Fig. 11 is a section along the line 11—11 of Fig. 4.

Fig. 12 is a plan view of a tool guide and clamping device.

Fig. 13 is a section along the line 13—13 of Fig. 12.

While I have shown in the drawings and shall herein describe in detail a preferred embodiment of my invention particularly adapted for sharpening cemented carbide tools, it is to be understood that I do not thereby intend to limit the invention to the specific form or arrangement disclosed, but aim to cover all modifications and alternative constructions falling within the spirit and scope of the invention as expressed in the appended claims.

As illustrated in the drawings, the invention comprises generally a frame or pedestal 20 (Fig. 1), a rough grinding wheel 21 and a finish grinding wheel 22 mounted on the opposite ends of a horizontal double ended spindle 23 rotatably mounted in the upper portion of the pedestal and projecting from the opposite sides thereof, a honing wheel 24 mounted on the front end of a spindle 25 rotatably mounted in the upper portion of the pedestal and extending forwardly therefrom, oscillatory work supports 26 and 27 adjacent the wheels 21 and 22 and an adjustable work support 28 adjacent the wheel 24. The grinding wheel spindles are arranged to be driven by an electric motor 29 (Figs. 2 and 4) positioned in the lower portion of the pedestal. The rough and finish grinding wheels are arranged to be supplied with coolant from a reservoir 30 by 35

means including a pump 31 and conduits 32 and 33.

In the preferred form of the invention the pedestal 20 comprises a hollow base portion 35 and a hollow top frame element or casing 36 secured thereon by means of bolts 37. The double ended spindle 23 is rotatably mounted in the upper portion of the casing 36 (Fig. 2) by means of anti-friction bearings 38 and 39 so arranged as to prevent end play of the spindle and to provide the necessary thrust support. The spindle 25 is positioned at right angles to the spindle 23 and is rotatably mounted by means of an antifriction bearing 40 in the forward wall of the casing, and a second antifriction bearing 41 mounted in a bracket 42 formed integrally with and extending inwardly from the forward casing wall, so as to provide bearings on the opposite sides of a pulley 43 on the spindle. This pulley as well as a double pulley 44 on the spindle 23 are connected with a multiple pulley 45 (Figs. 2 and 4) on the shaft of the motor 29 by means of belts 46, 47 and 48. In order to provide for adjustment of the tension in the belts the motor 29 is preferably mounted on a U-shaped angle iron member 49 pivoted at its bifurcated end to the forward portion of the base by means of bolts 50 and having its closed end adjustable by means of nuts 51 on a screw device 52 which is secured in the base and extends through a suitable aperture in the horizontal flange of the member 49. Preferably blocks of wood 53 are inserted between the angle iron member and the feet on the motor so as to absorb vibration and eliminate the transmission of noise between the motor and base. The front of the base has an opening therein, covered by a screen 67 so as to provide the necessary ventilation for the motor.

The work supports 26 and 27 for the rough and finish grinding wheels are preferably adapted for an oscillatory movement across the face of the wheels and also for a feeding movement toward the wheels and, as illustrated herein, are provided with angularly adjustable work holders 56 and 57 movable about axes extending transversely of the spindle 23. The means for mounting the work supports comprises a cylindrical bar 58 which extends through suitable apertures in the side walls of the casing 36 and projects outwardly therefrom and into cylindrical recesses 59 in the work supports, handles 66 being provided on the opposite ends of the support so that an operator may oscillate the work support manually. Since, in the preferred embodiment of the invention, the work supports 26 and 27, and the parts associated therewith, are substantial duplicates of each other, only one will be described in detail.

Referring more particularly to Figs. 1, 2 and 6, the bar 58 is shown as having a flat surface 60 on the lower side of its right hand end. A similar flat surface is provided on the other end of the bar. A flat ended cylindrical member or plug 61 is slidably mounted in a recess 62 in the lower portion of the support 27 and is arranged to engage the flat surface on the bar 58. In order to clamp the plug 61 against the bar so as to hold the work support rigid with the bar, a bushing 63 is threaded in the lower portion of the recess 62 and has a closed outer end to which is secured an operating handle 64. By screwing the bushing 63 upwardly the work support can be clamped in position. By loosening the bushing the work support may be oscillated through an angle determined by the amount of play between the plug 61 and the bushing. Preferably a coiled spring

65 is inserted intermediate the plug 61 and the closed end of the bushing 63 so as to have a tendency to return the work support to its normal horizontal position.

Means in the form of a screw and nut mechanism is herein provided for feeding the work support 27 longitudinally of the bar 58, a screw 70 carried on the bar 58 engaging a nut 71 rotatably mounted in the forward portion of the support 27. As illustrated most clearly in Fig. 6 the rear end of the screw extends into a recess 72 in the end of the bar 58 and has an annular member or collar 73 secured thereto forming the middle race of a double ball thrust bearing, and cooperates with a series of balls 74 and a race 75 to prevent movement of the screw toward the left, the race 75 abutting against the inner end of the recess 72. A series of balls 76, together with a race 77 cooperate to form the other portion of the thrust bearing. This race and set of balls are held in engagement with the collar 73 by means of a coiled spring 78 positioned intermediate the race 77 and a shoulder formed on an adjustable bushing 79 which is screw threaded in the end of the recess 72. The tension of the coiled spring 78 is in this way readily adjustable by means of the bushing 79 for a purpose hereinafter more fully set forth. The nut 71 is generally cylindrical in form and has a peripheral groove 80 in which an arcuate shoe 81 fits. This shoe is secured to a plate 82 forming a portion of the work support 27 by means of a set screw 83 so as to permit rotary movement of the nut 71 and prevent longitudinal movement thereof. The nut is arranged to be operated manually by means of a pair of handles 84 secured in diametrically opposed relation thereon.

It will be readily apparent that by rotating the nut 71 in one direction the support 27 will be moved longitudinally on the bar 58 in a corresponding direction and likewise by reversing the rotation of the nut the movement of the work support is reversed. The coiled spring 78 forms a part of a cushioning means arranged to limit the pressure of a tool being ground, against the grinding wheel. Thus, for example, if a tool is clamped on the upper surface of the holder 57 and the support 27 is fed toward the grinding wheel at too rapid a pace by means of the screw and nut mechanism, the feed screw 70 can move toward the right (Fig. 6) with respect to the bar 58 so that the pressure on the tool will be determined by the coiled spring 78.

In addition to this cushioning means, means is provided so that the work support 27 will not be moved toward and away from the grinding wheel during oscillatory movement thereof with respect to the bar 58. This means is herein disclosed as comprising, in addition to the rotary mounting means for the screw on the bar, a pair of members 85 (Fig. 8) secured to the member 82 in laterally spaced relation and having their adjacent sides engaging a flattened portion 87 on the screw 70. Thus when the work support 27 is oscillated, the nut 71 and also the screw 70 are oscillated with the support, the oscillatory motion of the screw with respect to the bar 58 being permitted by the double thrust bearing.

The work holder 57 (Figs. 1, 2, 5 and 6) which is mounted for angular adjustment with respect to the work support 27 about the ways extending transversely of the grinding wheel axis is herein shown as provided with arcuate bevelled surfaces 90 engaging corresponding bevelled ways 91 on the work support 27. The holder 57 is

arranged to be adjusted by means of a manually operable handle 92 secured on the outer end of a shaft 93 which is rotatably mounted on the support 27 and has a worm 94 on its inner end 5 engaging worm wheel teeth 95 formed on the adjacent periphery of the work holder 57. This worm and worm wheel also operate to hold the work holder in its adjusted position. Preferably a scale 96 is provided on one end of the work holder and cooperates with a zero mark 97 (Fig. 5) on the support 27 to indicate the angular position of the holder. As illustrated in the drawings the work holder is provided with a T-slot 98 extending parallel to the face of the grinding wheel, and is provided with a pair of diagonally extending T-slots 99 positioned at approximately 45° with the T-slot 98 and diagonally across the opposite corners of the work holder. These slots as pointed out more fully hereinafter, facilitate 10 the mounting of suitable tool guiding and clamping devices on the work holder.

As mentioned hereinbefore the work support 26 and its associated parts and operating mechanisms are substantial duplicates of the work support 27 with the exception that the angular adjusting means for the work holders are both placed adjacent the front side of the machine as shown in Fig. 5. The work support 28 for the honing wheel 24, however, may be different in 15 form because of the fact that when tools are being honed they are generally applied to the wheel manually by the operator.

As illustrated herein the work support 28 is carried on a cylindrical bar 105 which has one end rigidly secured to the front wall of the casting 36 (Fig. 4) and projects forwardly therefrom. A split clamping member 106 has an annular portion surrounding the bar 105 and a split part 20 extending upwardly therefrom. The work support 28 has a pair of laterally spaced downwardly extending brackets 107 engaging the opposite ends of the split portion of the clamping member, as shown in Figs. 1 and 11. A rod 108 extends through slots 109 in the split portion of 25 the clamping member 106 and through circular apertures 110 in the brackets 107, as illustrated most clearly in Fig. 11. The portion of this rod extending through the split portion of the clamping member is preferably flattened on opposite 30 sides so as to be held non-rotatably in the clamping member. The end portions 110 of the rod, however, are cylindrical so as to permit the work support 28 to be adjusted angularly. At one end the rod 108 is headed at 111, a portion of the 35 head being in the form of a bevelled collar 112 having graduations 113 thereon arranged to cooperate with a zero mark on the adjacent member 107 to indicate the angular position of the work support. The other end 114 of the rod is 40 threaded and carries a handle 115 a portion of which forms a clamping nut. Thus the clamping rod and nut just described perform three functions, the first of which is to secure the clamping member 106 to the bar 105, the second to secure 45 the work holder 28 to the clamping member 106, and the third to permit of angular adjustment of the work holder with respect to the clamping member. If desired a key 116 may be provided for holding the clamping member 106 in 50 its upright position. As illustrated most clearly in Figs. 4 and 5 the top of the support 28 forms a table-like structure extending in front of and along the sides of the grinding wheel 24, and is 55 preferably provided with a T-slot 117 in case an

operator finds it desirable to secure a guide or other device to the top of the support.

Protective hoods 120, 121 and 122 are provided for the grinding wheels and, as illustrated herein, are adjustable angularly and longitudinally of the wheels on cylindrical mounting members 123, 124 and 125, respectively, carried on the casing 36 so that, as the cup shaped wheels wear, the hoods may be moved back to leave the face of the wheels properly exposed. Suitable headed screw devices 126 (Fig. 5) are provided to secure the hoods in their adjusted positions. As illustrated in Figs. 1, 2 and 4, the coolant supply conduits 32 and 33 have valve devices 130 and 131, respectively, and connect to ports 132 and 133 formed in the upper portions of the hoods 120 and 121. Adjustable nozzle members 134 and 135 are threaded into the outer ends of the ports 132 and 133 and are arranged to direct the coolant against the cutting portions of the 20 wheels.

The invention provides a novel means for supplying cutter coolant. Thus as illustrated in Fig. 4, the rear side of the base is provided with an opening 136 and the tank 30 is fitted into said opening. The bottom of the tank is provided with a pair of laterally spaced lugs 138 arranged to straddle a portion of the rear wall of the base, and notched lugs 138' (Fig. 5) are provided on the top sides of the tank arranged to engage both sides of the rear wall of the base to secure the tank in an upright position. In this way it is merely necessary to lift the tank slightly by means of handles 139, to remove it from the base, the notched lugs then passing out through opposed recesses 136' (Fig. 2) which widen the opening 136 at the level of the lugs in the raised position of the tank. A partition wall 140 is shown herein centrally of the tank to divide it into compartments 141 and 142. Coolant is 40 drawn out of the compartment 141 through a pipe 143 which leads to the intake of the pump 31. The outlet of the pump is connected by means of a pipe 144 to the conduits 32 and 33. The coolant discharged against the grinding 45 wheels drains into the lower portions of the work supports 26 and 27 which are provided with side walls 26' and 27', cooperating with the bottom of the supports to form receptacles under and surrounding the tool holders. Pipes 145 and 146 50 carry the discharged coolant from these receptacles into the compartment 142 of the tank. As herein illustrated the partition wall 140 stops short of the top of the tank so that the used coolant can flow over the partition wall into the 55 compartment 141. This gives any sediment in the discharged coolant an opportunity to settle in the compartment 142.

The pump 31 is herein mounted on a plate 147 which is secured to a bracket 150, hung from the 60 bar 58, and adjustably clamped thereto by means of a screw device 151. The pump is provided with a pulley 152 mounted on a shaft 153 and has an outboard bearing 154 for the shaft. The pump pulley is so positioned as to engage the twisted 65 run of the belt 46 (which is V-shaped on both sides) and is not only driven by the belt 46, but serves as an idler and direction pulley for the belt, as illustrated most clearly in Fig. 2.

If desired, the tools being ground may be supported on the work holders and held manually against the wheels. If this is the case it is generally desirable to provide a guide means against which the tool may be held during the feeding or oscillatory movements of the work support. Such 75

a guide means for a tool is herein illustrated in Figs. 9 and 10, and in Figs. 1 and 5, in connection with the work holder 56. A cylindrical member 160 has an inverted T-shaped portion 161 operable in the T-slot 98 and is slidably longitudinally of the slot. An apertured rectangular member 162 fits over the cylindrical member 160 and is adjustable angularly thereabout, a screw device 163 being threaded in the member 162 with its inner end engageable in a groove 164 in the member 160, to secure the guide member 162 in its angularly adjusted position. Preferably a scale 165 on the member 160 cooperates with a zero mark 166 on the guide member 162 to indicate the angle 15 to which the guide member is adjusted. In use a tool 167 (Fig. 5) is held against a side of the guide member 162 during the grinding operation.

At times it is preferable to clamp a tool rigidly to the work holder and to control the feeding of the tool against the wheel by means of feeding mechanism for the work support. Such a clamping device is illustrated in Figs. 12 and 13 for clamping a tool 168. This device comprises a cylindrical post 169 having its lower end in the form of an inverted T slidably engaging in a T-slot on the work holder 56. A tubular bushing 170 surrounds the lower portion of the post 169 and has straight sided recesses 171 and 172 therein, the recess 171 receiving a portion of the tool 168. A collar 173 is non-rotatably secured on the upper end of the post 169 and carries a set screw 174 engaging in a keyway 175 in the post to prevent rotation of the collar with respect to the post. A headed clamping screw 176 extends 35 through a washer 177 on top of the collar 173 and into screw threaded engagement with the post. Since the bushing 170 is rotatable with respect to the post the tool 168 may be adjusted to any desired angle. This angle may be indicated by 40 means of a scale on the bushing 170 cooperating with a zero mark on the collar 173, since the position of the collar is fixed with respect to the T-slot by means of a set screw 174. After the proper angular adjustment the clamping screw 176 45 may be tightened and the tool 168 then moved by oscillating or feeding the work support.

It will be readily apparent that as disclosed herein the invention provides a grinding machine capable of performing rough grinding, finish 50 grinding and also honing operations, and that the work supporting and feeding mechanisms permit of holding the tools accurately at desired angles and maintaining these angles during the grinding of the tool. The provision of means for 55 cushioning the feeding of the tool against the grinding wheels effectively prevents any injurious pressures on the tool, and the novel form of feeding mechanism eliminates any possibility of the tool being fed toward the wheel during the oscillatory movement of the work holders. The result is a machine particularly adapted for the 60 grinding and finishing of tools such as those made of cemented carbide, as well as other materials.

I claim as my invention:

65 1. In a grinding machine of the character described having a hollow pedestal, a first grinding wheel spindle rotatably mounted in said pedestal and projecting from a side wall thereof, a second grinding wheel spindle rotatably mounted in the 70 pedestal and projecting from the front wall thereof, pulleys on said spindles, an electric motor in the pedestal and having a driving shaft parallel to one of said spindles, a multiple pulley on said driving shaft, a belt connecting said multiple pulley with the pulley on the parallel spindle, a

second belt connecting said multiple pulley with the pulley on the other spindle through a quarter turn, a cylindrical work support mounting bar extending into and projecting out from said pedestal parallel to one of said spindles, a bracket 5 secured to said bar within the pedestal, and an idler pulley rotatably mounted on said bracket for guiding said quarter turn belt.

2. In a grinding machine having a cylindrical supporting bar and a work support mounted for feeding movement longitudinally of the bar and oscillatory movement about the bar, means for feeding the work support comprising a feed screw coaxial with said bar and having one end positioned in a recess in one end of the bar so as to 10 project therefrom, a double thrust antifriction bearing having its center race secured to said screw, one end race positioned against the bottom of said recess and the other end race surrounding the screw, a bushing threaded into said 15 recess, a coiled spring positioned intermediate said bushing and the adjacent race of the bearing, a nut for said screw rotatably mounted on the work support, means for preventing longitudinal movement of the nut relatively to the work 20 support, means for rotating said nut, and means for preventing rotation of said screw relatively to the work support.

3. In a grinding machine having a cylindrical supporting bar and a work support mounted for 30 feeding movement longitudinally thereof and oscillatory movement thereabout, means for feeding the work support comprising a feed screw coaxial with said bar and having one end positioned in a recess in one end of the bar so as to 35 project therefrom, a double thrust antifriction bearing having its center race secured to said screw, one end race positioned against the bottom of said recess and the other end race surrounding the screw, a bushing threaded into said recess, a 40 coiled spring positioned intermediate said bushing and the adjacent race of the bearing, a nut for said screw mounted on the work support, and means for rotating one element of the screw and nut device. 45

4. In a grinding machine having a cylindrical supporting member constituting a first part and a work support mounted for feeding movement longitudinally thereof and oscillatory movement thereabout and constituting a second part, means 50 for feeding the work support comprising a feed screw and nut device, one element of which is carried on one of said parts and the other on the other part, a double thrust antifriction bearing having its center race secured to one of said elements, one end race positioned against its supporting part and the other end race surrounding the element, a bushing threaded onto said part, a coiled spring positioned intermediate said bushing and the adjacent race of the bearing, means 55 for preventing longitudinal movement of the other element of said device relatively to the supporting part, means for rotating one of said elements, and means for oscillating the element on the work support with the work support. 65

5. In a grinding machine having a cylindrical supporting bar and a work support mounted for oscillatory movement about the bar, and means for limiting the oscillatory movement of the support comprising a part slidably mounted on said work support for movement substantially radially of the bar and arranged to engage a flattened portion of said bar, a member adjustable on said support to limit the movement of said part away from the bar and thereby limit the oscillatory 70 movement of the support. 75

movement of the support, a coiled spring positioned intermediate said member and said part pressing said part against said flattened surface of the bar and tending to return the work support to its normal position, and a manual control device for adjusting said member.

6. In a grinding machine having a cylindrical supporting bar and a work support mounted for oscillatory movement about the bar, and means for limiting the oscillatory movement of the support comprising a cylindrical plug slidably mounted in a recess in said work support for movement substantially radially of the bar and arranged to engage a flattened portion of said bar, a bushing threaded in said recess and adjustable to limit the movement of said plug away from the bar and thereby limit the oscillatory movement of the support, a coiled spring positioned intermediate said bushing and said plug pressing said plug against said flattened surface of the bar and tending to return the work support to its normal position, and a manual control device for operating said bushing, said bushing being adapted to be rotated sufficiently to force said plug firmly against the flattened surface of the bar so as to clamp the work support rigidly to the bar and prevent oscillatory movement of the work support.

7. In a grinding machine having a cylindrical supporting member constituting a first part, and a work support mounted for feeding movement longitudinally thereof and oscillatory movement thereabout and constituting a second part, means for feeding the work support comprising a screw and nut device, one element of which is carried on one of said parts and the other on the other part, a double thrust bearing having its center race secured to one of said elements, one end race positioned against the supporting part of that element and the other end race surrounding that element, a member threaded onto said last mentioned part, a coiled spring positioned intermediate said member and the said other race of the bearing, means for preventing longitudinal movement of the other element of said device relatively to its supporting part, means for rotating one of said elements, and means for oscillating the element on the work support with the work support.

8. In a grinding machine having a cylindrical supporting member constituting a first part, and a work support mounted for feeding movement longitudinally thereof and oscillatory movement thereabout and constituting a second part, means for feeding the work support comprising a feed screw and nut device, one element of which is carried on one of said parts and the other on the other part, a double thrust antifriction bearing having its center race secured to one of said elements, one end race positioned against its supporting part and the other end race surrounding the element, a bushing threaded onto said part, a coiled spring positioned intermediate said bushing and the adjacent race of the bearing, means for preventing longitudinal movement of the other element of said device relatively to the supporting part, means for rotating one of said elements, and means for preventing relative movement between the said elements when the work support is oscillated.

9. In a grinding machine having a support, a grinding spindle rotatably mounted on a horizontal axis and projecting from said support, a cup shaped grinding wheel on said spindle, a cylindrical bar extending from the support beneath

and parallel to the spindle axis, a work support mounted on the free end of said bar, a work holder mounted for angular adjustment on said work support about an axis extending transversely of the spindle axis, means for adjusting the angular position of said work holder including a manual control handle mounted on said work support in front of said grinding wheel, means for feeding said work support longitudinally on said bar including a second manual control handle mounted on said work support in front of said grinding wheel, and means for limiting the oscillatory movement of the work support on the bar and for clamping the work support to the bar including a manual control handle positioned beneath the work support.

10. In a grinding machine having a support a grinding spindle rotatably mounted on a horizontal axis and projecting from said support, a cup shaped grinding wheel on said spindle, a cylindrical bar extending from the support beneath and parallel to the spindle axis, a work support mounted on the free end of said bar, a work holder mounted for angular adjustment on said work support about an axis extending transversely of the spindle axis, means for adjusting the angular position of said work holder including a manual control handle mounted on said work support, means for feeding said work support longitudinally on said bar including a second manual control handle mounted on said work support, and means for limiting the oscillatory movement of the work support on the bar including a manual control handle mounted on the work support.

11. In a grinding machine of the character described having a hollow pedestal, a first grinding wheel spindle rotatably mounted in said pedestal and projecting from a side wall thereof, a second grinding wheel spindle rotatably mounted in the pedestal and projecting from the front wall thereof, pulleys on said spindles, an electric motor in the pedestal and having a driving shaft parallel to one of said spindles, a multiple pulley on said driving shaft, a belt connecting said multiple pulley with the pulley on the parallel spindle, a second belt connecting said multiple pulley with the pulley on the other spindle through a quarter turn, a bracket adjustably mounted within said pedestal, secured to said bar within the pedestal, means for supplying coolant to one or more grinding wheels on said spindles including a pump mounted on said bracket, and a drive pulley for said pump engaging said quarter turn belt so as to act as a guide for the belt and to be driven therefrom.

12. A tool-sharpening machine comprising, in combination, a hollow pedestal adapted for floor mounting and of relatively large substantially rectangular horizontal cross section, rough and finish grinding wheels, a first spindle on said pedestal rotatably supporting said wheels on horizontal axes substantially waist-high and facing outwardly from the pedestal on opposite sides thereof, work supports mounted on said pedestal beneath said grinding wheels for oscillatory movement transversely of the grinding wheel axes, means for feeding said supports toward the grinding wheels axially thereof, a honing wheel, a second spindle rotatably supporting said honing wheel substantially waist-high on a horizontal axis and extending outwardly from the forward side of the pedestal, a work support carried by said pedestal beneath said honing wheel, a coolant supply reservoir mounted on

the rear side of said pedestal, a pump mounted within said pedestal, and an electric motor mounted within said pedestal adjacent to the bottom thereof and having a belt driving connection with said first spindle and a single belt driving said pump and said second spindle.

5 13. A grinding machine having, in combination, a frame comprising a hollow base pedestal and a top frame element detachably secured thereon, a spindle journaled in said top frame element and projecting therefrom to receive a grinding wheel, a supporting bar also projecting from said top frame element, a work support mounted on said bar, and a coolant supply reservoir 10 removably mounted in and forming part of a wall of said base pedestal.

14. In a grinding machine having a cylindrical supporting bar and a work support mounted thereon for feeding movement longitudinally of 15 the bar and oscillatory movement about the bar, means for feeding said work support during a grinding operation comprising a feed screw and nut device, one element of which is rotatably

carried on said bar and the other is rotatably carried on said support, means for rotating one element of said device to feed the support, and means for oscillating the element carried on said bar with said support when the same is oscillated to prevent feeding movement of the support by relative rotation of the elements.

15. In a grinding machine having a cylindrical supporting bar and a work support mounted thereon for feeding movement longitudinally of 10 the bar and oscillatory movement about the bar, means for feeding said work support during a grinding operation comprising a feed screw rotatably supported at one end by said bar, a nut threaded onto said screw and rotatably mounted 15 on said support, means for rotating said nut to feed the support longitudinally of said bar, and means on the support engaging said screw to oscillate the same with said support to prevent feeding movement of the support by relative rotation of the screw and nut when the support is oscillated.

PAUL S. JACKSON.
